CLAIM

The ornamental design for a mobile ophthalmoscope, as shown and described.

DESCRIPTION

FIG. 1 is a rear perspective view of a mobile ophthalmoscope;

FIG. 2 is a rear elevation view of the mobile ophthalmoscope of FIG. 1;

FIG. 3 is a front elevation view of the mobile ophthalmoscope of FIG. 1;

FIG. 4 is a first side elevation view of the mobile ophthalmoscope of FIG. 1;

FIG. 5 is a second side elevation view of the mobile ophthalmoscope of FIG. 1;

FIG. 6 is a top view of the mobile ophthalmoscope of FIG. 1; and,

FIG. 7 is a bottom view of the mobile ophthalmoscope of FIG. 1.

The broken lines depict portions of the mobile ophthalmoscope that form no part of the claimed design.

1 Claim, 7 Drawing Sheets
